UNITED STATES PATENT OFFICE.

JOHN LAWSON, OF CENTRAL FALLS, RHODE ISLAND.

AUTOMATIC CIRCULAR-KNITTING MACHINE.

1,111,844.

Specification of Letters Patent. Patented Sept. 29, 1914.

Application filed January 27, 1912. Serial No. 673,712.

To all whom it may concern:

Be it known that I, JOHN LAWSON, a citizen of the United States, residing at Central Falls, in the county of Providence and State of Rhode Island, have invented certain new and useful Improvements in Automatic Circular-Knitting Machines, of which the following is a specification.

This invention relates to improvements in automatic circular knitting machines, and it consists in certain novel features of construction and combination hereinafter set forth and claimed.

It may be stated in advance that while the drawings herewith represent portions of an automatic knitting-machine of the revoluble-cylinder type (such, for example, as disclosed in J. D. Hemphill's U. S. Patent #933,443 of September 7, 1909), the improvements forming the subject of this application are not limited to knitting-machines of the revoluble-cylinder type, but are capable of being employed in knitting-machines having non-revoluble knitting-cylinders; therefore the claims are not limited to either type of knitting-machine.

In the accompanying two sheets of drawings, Figure 1 represents a partial end elevation, partly in section, showing portions of an automatic circular knitting-machine embodying my invention, the parts being in the normal operative position, as in producing plain knitting; Fig. 2 is a partial rear side elevation, corresponding substantially with Fig. 1; Fig. 3 is a vertical central section through the needle-cylinder (in enlarged scale) showing the thread-cutter and web-cutter mounted on the latch-ring, the parts being in the normal or inactive position; Fig. 4 is also a vertical central section, showing the upper portion of the cylinder and contiguous parts, the thread-cutter being in the temporarily open position; Fig. 5 is a partial plan view of the parts shown in Fig. 4; Fig. 6 is a sectional view similar to Fig. 4, except that the thread-cutter is not shown, while the web-cutter is represented in the act of severing the web; Fig. 7 is a top plan view of the swinging latch-ring, having the thread-guides, thread-binder, thread-cutter and web-cutter mounted thereon and adapted for movement with the latch-ring; and Fig. 8 is a front elevation, in reduced scale, and partial section, showing portions of the upper part of the machine.

The said drawings represent what I consider the preferable way of actuating and controlling the movements of the several devices. That is to say, the initial actions of the latter are adapted to be governed by suitably shaped cams, or analogous members, mounted, positioned and timed with relation to one another on what may be termed a master-shaft s^1 , whose angular movements may be effected in an intermittent manner by a pattern-chain. It may be added that in circular knitting-machines the said main or master-shaft is usually adapted to make only one revolution during the production of each knitted unit or tubular web, as for example, a stocking.

It is assumed that the assembled parts or elements comprising modern automatic circular knitting-machines (and including the manner of operation) of the general type referred to are well-known to knitters (except as to the specific mechanism and manner of mounting the thread and web-cutting devices); therefore a more detailed representation and description are deemed unnecessary in the present application for patent. In order, however, to more clearly set forth the relation of the newer cutting devices to coöperating members of this type of knitting-machine, certain parts of the latter are shown herewith:

The knitting or needle-cylinder D is adapted to be provided with a sinker-ring f , cap-ring f^1 , and other coöperating parts or elements necessarily employed in connection therewith for knitting, and supported on a main frame a . The machine is also provided with a fixed rear standard c^1 capable of being engaged by the cap-ring, and having the latch-ring c hinged thereto. The latch-ring has a lateral extension c^4 (see Figs. 7 and 8) carrying one or more thread-guides d^2 pivoted at d^3 to its outer end; the thread-guides are adapted to place the respective threads in and out of knitting action by suitable means capable of vertically moving links v^1 , connected respectively to tilting fingers v adapted to engage the underside of the guides. In order to simplify, as well as to lessen the cost of construction of certain devices, say those for temporarily clamping or binding the thread, for cutting the thread, and for severing the web, and at the same time render the devices readily accessible, the latter may be supported for operation on a normally station-

ary plate or base b^1 . I prefer, however, to provide the plate with a bent lateral arm b adapted to be secured to the top of the rearward arm c^2 of the latch-ring; the said plate portion being disposed substantially centrally of the latch-ring and within the circular needle-row at a point immediately above the top of the needle-cylinder. As thus constructed and arranged, it is obvious that said devices for acting on the thread and web, and including the thread-guides, are capable of angular or swinging movements bodily with the latch-ring; the latter's movement at the same time in no wise materially affecting or changing the condition and relative positions of the devices to one another.

The following is a more detailed description of the construction and manner of operation of the thread-clamping and web-severing devices above referred to: The thread-clamping device is provided with a journaled bent wire having its clamping arm proper, d^1 , normally bearing on the face of said plate b^1 . The said thread-clamp is adapted to be readily actuated by hand, if desired, while the thread-cutter is in the normally closed position. The thread-cutting device consists of a main operating-lever h , pivotally supported at h^1 on the top of said plate-carrying arm b ; the inner portion m^2 of lever h is jointed to a cutting-jaw m , in turn pivoted to the plate; the jaw is arranged and adapted to coact with a relatively stationary steel blade m^1 removably secured to the plate. Means represented for automatically actuating and controlling the movements of said thread-clamping and thread-severing devices may be described as follows:

To the master-shaft s^1 , which is capable of being actuated by a pattern-chain in a step-by-step manner, is secured a disk-cam i (Fig. 1) having lugs i^1 suitably positioned on its rim; the front or free end of a lever g , pivoted at g^2 , is arranged in the path of said cam so that when the lever and either of the cam-lugs i^1 are in temporary engagement, the rod g^1 jointed to the lever g and to lever g^2 (Fig. 2), causes the latter, jointed to vertical rod g^3 , in turn joint-connected to the slotted arm of lever h , to vibrate the other arm m^2 downward, which, in connection with the pivoted cutting-jaw m , opens the jaws, as before stated. To the arm m^2 is secured a downwardly extending member s^2 , the latter having its lower end normally engaging a short arm o , adjustably secured to the binder or threading clamping arm d' in connection with a spring s^5 vertically interposed between and attached to said members m^2 and o , causes both the binder d' and thread-cutting jaw m to open when the lever g and a lug i^1 are in engagement.

The web-cutting device represented con-

sists essentially of a tilttable slotted two-arm lever h^4 , supported on a pivot h^1 of said stationary member b secured to the latch-ring; the inner end of the lever being jointed at 1 (Fig. 6) to the upper portion h^5 of a movable element pivoted at h^6 to the plate b^1 , and having the lower part or stem h^2 extending freely downward a suitable distance through an opening h^7 in the plate. The steel web-cutter k has a circular form, 75 its periphery being ground to a cutting edge. The cutter itself is supported by and freely revoluble on the lower end of the stem h^2 , as clearly shown. At a point below the sinkers upon the inner face of the 80 wall of the annular needle-cylinder D is located a ring k^1 of brass or other metal of less hardness than the cutter for the latter to bear against when it is swung from the normal vertical position to the outward or 85 cutting position.

The drawings show means for moving the web-cutter k , as follows: A cam e is adjustably secured to the main cam-shaft s^1 ; the cam has a short lug e^1 disposed on its 90 periphery, Figs. 1 and 2. A lever e^2 , pivoted at e^3 , is in normal engagement with said cam, the rear end of the lever being connected to a vertically extending rod e^4 , in turn jointed to a lever e^5 pivoted at e^6 to the 95 top of frame a . The other end of lever e^5 is jointed to a vertical rod e^6 , in turn connected to and arranged to actuate said slotted lever h^4 , and located substantially parallel with lever h , before described. Stationary brackets n^1 and n^2 serve to guide the rods e^6 and g^3 , respectively. The function of spring s^3 , pressing against the underside of bracket n^1 , in connection with the collar s^4 , 100 adjustably mounted on rod e^6 , is to automatically return the web-cutter k to the normal inoperative position immediately after the cutter has severed the web. 105

In Fig. 6 z indicates the point at which the web is severed. This point may be 110 varied, if desired, by simply lengthening or shortening the cutter-carrying stem h^2 .

It is obvious that the latch-ring c (including the said devices mounted thereon for guiding, binding and severing the 115 thread, and also carrying the web-cutter) may be swung on its stationary pivot p , as indicated by the broken line x in Fig. 3; the inner broken line x^1 indicates the course of the movement described by the outer edge 120 of the web-cutter when the latch-ring is being angularly moved.

It is, of course, understood that the product or web w is being continuously and normally knitted and moves downward in the 125 tube t . In the drawings the cylinder D is mounted for rotation; the arrows indicating the direction of normal movement. As thus arranged the knitted output is sometimes termed "string work", the web w being sub- 130

sequently cut into unitary lengths by hand. In case the knitted product is stockings, as for example, ladies' hose, the web-cutter is capable of being automatically brought into cutting action immediately succeeding the knitting of the toe part, the machine then normally producing continuous circular courses of stitches. By means of the web-cutter's action, the thus severed stockings are uniform in length (corresponding to the adjustment and timing of the cutting mechanism), while the line of severance is true or even, therefore much less waste stock is produced in looping. At the same time, the arrangement insures greater accuracy and efficiency, since the work is not "run off" from the needles, and rendering the latter empty. In machines where the thread is "run-on" to empty needles, preliminary to knitting the next stocking, the running-on action involves inherent disadvantages not present in the present case. The simultaneously rotating cylinder and web w , in coöperation with the temporarily positioned, relatively stationary cutter k (Fig. 6) when pressing against the inner surface of the web, causes the cutter to freely revolve on its axis and cut the web roundabout at the line or point z , the thus severed web part immediately falling and leaving the other or shorter part w^1 of the web supported on the needles (see arrow). The cutter instantly returns to its vertical normal position after the severing action is effected.

It may be noted that the construction and arrangement of the parts represented in the drawings are such that the web-cutter is adapted to be moved into cutting action by the cam-lug e^1 , the force of the spring s^3 returning the cutter inward to the vertical or normal position away from the knitted tubular web w . The drawings also represent the movable thread-cutting member m , adapted to be opened or swung downward upon the engagement of the lever g with a cam-lug i^1 . The spring s^2 causes the said thread-cutting jaw, in coöperation with the relatively stationary cutting-blade m^1 , to quickly sever the thread and remain in the thus closed or normal position until the ad-

vancing cam-lug, in its intermittent movement, is again engaged by the lever g .

I claim:

1. In a full automatic circular knitting-machine provided with a revoluble annular needle cylinder, a latch-ring mounted to swing above the cylinder, and a base plate member fixed to the latch-ring, the combination therewith of a fabric-cutter located within the cylinder, said cutter carried by an arm pivoted to the base-plate, a revoluble cam, and instrumentalities connecting said cam and arm arranged and timed for causing the cutter to swing into and out of cutting action. 65
2. In an automatic circular knitting-machine having a needle-cylinder, the combination of a web-cutter, a movably positioned plate or base disposed within the needle-row having said web-cutter pivotally supported therein, and means for swinging the web-cutter to engage an inner circular surface of the needle-cylinder. 70
3. In an automatic circular knitting-machine provided with a needle-cylinder and the usual stitch-forming means, the combination of a plate element movably mounted above the top of the cylinder, a swinging web-cutter capable of independent movement, supported on said plate, and means for moving the web-cutter outward against an inner surface of the needle-cylinder to engage and transversely sever the tubular web extending downward between said inner surface of the cylinder and the periphery of the web-cutter. 75
4. In an automatic circular knitting-machine having a needle-cylinder and a pivoted latch-ring normally positioned thereabove, the combination therewith of a pivoted web-cutter supported on the latch-ring and bodily movable with it, and means for moving the web-cutter in and out of cutting action to sever the web. 90

In testimony whereof I have affixed my signature in presence of two witnesses.

JOHN LAWSON.
